UNITED STATES PATENT OFFICE.

MORLAND MICHOLL DESSAU, OF LONDON, ENGLAND.

ROADWAY, PAVEMENT, STAIRWAY, OR THE LIKE AND MATERIALS FOR THE CONSTRUCTION THEREOF.

Application filed October 29, 1923. Serial No. 671,560.

To all whom it may concern:

Be it known that I, MORLAND MICHOLL DESSAU, a citizen of the United States of America, residing at London, England, have ⁵ invented Improvements in or Relating to Roadways, Pavements, Stairways, or the like and Materials for the Construction Thereof, of which the following is a specification.

¹⁰ This invention relates to roadways, pavements, stairways and the like of the kind in which the wearing surface consists wholly or partly of rubber in relatively small pieces, the rubber being embedded in ¹⁵ concrete or the like before the latter sets.

The principal object of the invention is to provide an improved surface for use where such qualities as resistance to wear, reduction of noise, freedom from slipping ²⁰ and cheapness are preeminently desired.

According to my invention each piece of rubber, in order to make it a self-contained unit, is provided, before being placed in the concrete, with simple means for anchoring it therein, the said means consisting either in shaping the piece of rubber with a kind of waist by making its cross-sectional area at the top and bottom greater than at an intermediate part, or in providing it ²⁵ with a piece of wire, or the like bound tightly around said intermediate part, thereby binding same and producing a cross sectional area of greater dimensions at both top and bottom than at an intermediate ³⁰ point and gradually increasing from said point toward the top and bottom of the rubber piece or block.

One of the advantages of the invention is that the inter-relationship between the rubber and the concrete or other binding agent ⁴⁰ is such as to render the latter, which is the brittle constituent, less liable to fracture and break away at the regions adjacent to the rubber, whether the surface be of a ⁴⁵ composite nature, that is to say, presenting rubber in alternation with the binding agent or one in which rubber alone is exposed to wear. This is achieved by arranging that the edge of the binding agent adjacent to ⁵⁰ the rubber shall not be vertical, or, if vertical, shall not extend continuously to such a depth as to render the binding agent liable to give way or crush under the load or traffic ⁵⁵ which the surface is destined to carry. For example, when the rubber is distributed in

the form of blocks the horizontal cross-sectional dimensions of which are smaller at a distance from the wearing surface than at such surface, the change may take place either gradually or in a stepped fashion. In ⁶⁰ this way the binding medium, which is complementary to the rubber, increases in cross-sectional dimensions as the surface is recessed from.

In connection with pavements consisting ⁶⁵ of bricks or wood blocks on a concrete foundation it has already been suggested that the sides and ends of the bricks or blocks should be hollowed out so that the concrete or other plastic material entering the hollows will form a dovetail or key to hold the blocks in position.

Various suggestions have been made for the construction of pavements wherein blocks of rubber are secured to a concrete ⁷⁰ foundation by moulding them to fit anchoring members embedded in the concrete or to fit mating apertures formed in the concrete, or wherein sheets of rubber provided with a plurality of projecting anchoring devices on the under side are pressed ⁷⁵ into a layer of concrete while the latter is in a plastic condition; or wherein a tile comprises a body of india rubber and one or more plain metal or other studs embedded ⁸⁰ at one end therein during moulding or integral studs adapted to be tapped into place in a cement or like foundation.

The invention will be more readily understood from the description now about ⁸⁵ to be given of the same with the aid of the accompanying drawings whereof Figs. 1 to 7 are sectional views of different modifications.

According to one construction exemplified ⁹⁰ in Fig. 1, blocks *a* of rubber may be used having heads *b* the under surfaces of the overhanging portions of which are inclined or bevelled somewhat as shown. In this case the binding agent *c* will similarly have ⁹⁵ a bevelled or inclined wall so that an edge results which is better adapted to withstand damage due to pressure or blows imparted to it. The anchorage is due, in the construction shown in this and the next four ¹⁰⁰ figures, to enlargement of the rubber mass at the base.

In an analogous way, as exemplified in ¹⁰⁵ Figs. 2 and 3, the blocks of rubber may have square-edged overhanging portions *d*, which

blocks, if they be disposed as in Fig. 2 (so that the heads do not actually engage, as they do in Fig. 3) will leave spaces for reception of the binding agent between the 5 overhanging parts, the vertical depth of which is short compared to the width of the blocks and of the spaces between the overhanging parts thereof, the intervening concrete therefore taking a form which makes 10 it better able to resist the stresses and shocks to which it is subject. The walls proceeding from the upper surface may however be in addition inclined or bevelled, as indicated in Fig. 4.

15 Fig. 5 illustrates a modification in which the blocks α have stepped overhanging portions c .

The required surface may be produced by first applying the plastic binding agent to 20 the body to be covered and then embedding the rubber therein; or the rubber and binding agent may be fashioned into slabs or blocks, in conjunction with other material or not, and be laid like ordinary wood 25 blocks or paving stones.

Where the blocks are small, rubber which has been used for other purpose and since discarded can be cut to shape and utilized, in which case the cost of manufacture may 30 be considerably reduced.

The invention may be variously carried into effect. For example "made" rubber, after being cut or formed into blocks of a regular size or shape, may, as shown in Fig. 35 6, be thereafter tightly bound with a wire f or wires leaving twisted and projecting ends or portions g which will serve to key the same in a mass of Portland cement for example. Conveniently the requisite number 40 of pieces of rubber individually treated in this manner may be assembled in a "former," into which liquid cement is subsequently poured and afterwards allowed to set, the "former" being for a time vibrated or the 45 cement subjected to pressure to consolidate the whole if so desired. Also, as indicated in Fig. 7, if it be intended to apply the surface to a wood block h for example, the latter, appropriately undercut, may be forced 50 into the cement before the latter sets. As will be apparent, many modifications of this method may be adopted, the rubber being for instance forcibly inserted through rings of metal adapted to serve as keys for holding 55 the same securely in the binding agent, which similarly need not be Portland cement but any other medium of appropriate hardness when solidified.

What I claim is:—

1. A wearing surface of the character described, consisting of self-contained units of rubber in relatively small pieces embedded in a plastic binding agent before the latter sets; the several units each having a cross sectional area greater at the top and bottom 60 thereof than at an intermediate point, whereby said units are permanently and immovably secured in spaced relation in the body of the binding agent when the latter sets. 65

2. A wearing surface of the character described, consisting of rubber blocks embedded in concrete before the latter sets; the several blocks having each a cross sectional area which enlarges in horizontal dimensions from an intermediate point toward both the 70 top and bottom thereof, and pieces of wire bound tightly around the blocks at said intermediate points and serving to reduce their cross-sectional area at said points, whereby the blocks are firmly anchored in the 75 concrete. 80

3. A wearing surface of the character described, comprising relatively small pieces of rubber embedded in the concrete before the latter sets; said rubber pieces having a 85 greater cross-sectional area at the base and top thereof than at an intermediate point and each provided with means for anchoring it in the concrete; said means consisting of a piece of wire wound tightly around 90 and binding the rubber piece at said intermediate point and serving to produce the aforesaid greater cross-sectional area above and below said point. 95

4. A wearing surface of the character described, consisting of pieces of rubber embedded in a plastic binding agent before the latter sets, and having pieces of wire bound tightly therearound at a point between the top and bottom thereof and serving to reduce their cross-sectional area at said point; the ends of the wires being twisted and projecting so as to serve to key the same in the concrete, whereby said rubber pieces are 100 firmly anchored in the concrete. 105

5. A paving block consisting of a piece of rubber having a piece of wire secured thereto with end portions of the wire projecting therefrom and adapted to serve as an anchoring means for securing the rubber in a solidified mass of concrete in which the rubber is embedded before the concrete sets. 110

Signed at London, England, this 19th day of October, 1923.

MORLAND MICHOLL DESSAU.
